J. E. SCOTT,
SHOE AND METHOD OF MAKING SAME.
APPLICATION FILED DEC. 29, 1915.

1,260,945.

Patented Mar. 26, 1918.

INVENTOR,
John E. Scott,
BY Clyde L. Rogers
his ATTORNEY.

UNITED STATES PATENT OFFICE.

JOHN E. SCOTT, OF MARBLEHEAD, MASSACHUSETTS, ASSIGNOR OF ONE-HALF TO
THOMAS C. ROWEN, OF SWAMPSCOTT, MASSACHUSETTS.

SHOE AND METHOD OF MAKING SAME.

1,260,945.

Specification of Letters Patent. Patented Mar. 26, 1918.

Application filed December 29, 1915. Serial No. 69,274.

To all whom it may concern:

Be it known that I, JOHN E. SCOTT, a citizen of the United States, and resident of Marblehead, county of Essex, Commonwealth of Massachusetts, have invented an Improvement in Shoes and Methods of Making Same, of which the following description, in connection with the accompanying drawings, is a specification, like characters 10 on the drawings representing like parts in each of the several views.

This invention relates to shoes, more particularly, though not exclusively, to children's shoes and to an improved method of 15 making the same. One important object of the invention is to provide a shoe of the so-called "turn" type that combines and embodies also the principal advantages of the welt type of shoe, such as increased wearing 20 quality, capability of retaining its shape through a long period of use and of being tapped or half soled when required. A further object is to provide an improved method of making such a shoe by a modification of 25 the turn system. The invention will be better understood from the following detailed description taken in connection with the accompanying drawings and will be thereafter pointed out in the appended claims.

30 Referring to the drawings:

Figure 1 is a plan view showing the bottom of a shoe constructed in accordance with my invention with the welt applied to the middle and outer soles;

35 Fig. 2 is a lengthwise vertical section through the bottom of the shoe with a heel piece in place;

Fig. 3 is a similar lengthwise section showing the bottom of the shoe without a separate 40 heel piece;

Fig. 4 is a partial lengthwise section showing the front of the shoe before it is "turned," but with the upper stitched to the welt; and

45 Fig. 5 is a similar partial section showing the front of the shoe after the shoe is "turned."

An outer sole is indicated at 10 of suitable thickness and outline. On this is superposed 50 another sole member 11 which may be termed a "middle" sole and to which a welt 12 has been previously stitched by stitching 13. The middle sole 11 and the welt 12 are then secured to the outer sole 10 by another stitching line 14 which extends through all three

of the said layers a little distance without the stitching line 13. If desired a heel piece 15 may be inserted between the outer sole 10 and the middle sole 11, such heel piece being shown in Fig. 2, while in Fig. 3 is shown the 60 bottom of a shoe without any separate heel piece to build up the heel. This heel piece may be nailed in place if desired but is preferably inserted in place before the stitching line 14 is produced, and said stitching passed 65 through this heel piece as well, to hold it in assembled relation with the sole members. The built-up sole thus constituted, with or without the inserted heel piece 15 is thus a complete and permanently assembled unit 70 before the upper is applied thereto, and it is to be noted that the formation and relative arrangement of the parts including the welt 12 is such that the upper is adapted to be applied, and the shoe finished, by the well 75 known "turn" method of shoe making. For this purpose the welt 12 as shown is relatively thin and applied to the middle sole 11 by the stitching 13 in a manner so as to leave a substantial inner edge portion thereof entirely free and in position to receive the stitching 17 for securing the upper, without having the upper stitching 17 intersect or cross the stitching line 13 which secures the 80 welt to the middle sole; this being an important point, as in cases where stitching lines thus intersect, the sharp point of the needle in applying the later stitching line is apt to cut the stitches of the line first produced and thus weaken the seam. I believe 85 that the present shoe is the first adapted to be produced by the "turn" system and equipped with a separate outer sole, such as the outer sole 10 adapted to protect the stitching line 13 which secures the welt, as 90 well as providing a capability of repairing, greater durability, cheapness, etc. The shoe bottom thus constituted is fitted on a last L and the upper 16 secured thereto by stitching 17 through the welt and the edge of said 100 upper. Thereupon the shoe is turned, a filler piece 18 either integral or of composition, applied to fill in the cavity made by the welt and an insole 19 fitted in completing the make up of the shoe. The insole 19 as 105 seen in Fig. 5 fits the peripheral outline of the shoe covering the roughness that would otherwise result from the projecting edge of the upper and from the edges of the exposed filling piece 18.

Among the distinctive advantages of the present construction is that the wear of the full thickness of the outer sole 10 is obtained before the stitching 13 which holds the welt 12 is exposed at all. Further during all this period of wear the shape of the shoe is retained intact by the middle sole 11, and will in fact be retained until this middle sole which in a sense corresponds to the inner sole of a welt shoe, is well worn out. With my improved construction the middle sole 11 can be made of cheaper leather than would ordinarily be required for an inner sole or for an element serving the functions of the sole 11. I believe it to be also new in my present construction to provide for inserting or applying one or more heel pieces such as the heel piece 15 and fastening the same before the shoe is turned. I also consider it to be a new and valuable feature of invention to provide for permanently applying and securing both heel and outer sole before the shoe is turned. It will be noted that a shoe constructed as described can be tapped or half soled readily since there is a substantial backing formed by the middle sole 11 and the welt 12 to which a new half sole may be secured; this being impossible in the ordinary turn shoe type. While the heel pieces 15 are preferably secured in place by the same stitching 14 that secures the two soles and the welt together, it will be understood that if desired this stitching at the back may be omitted and the heels inserted and nailed or otherwise secured. I also consider it to be a new and valuable improvement to produce a securing seam in a double sole before turning the same, this being obviously easier and more convenient. I do not desire to be limited to the precise structural details herein exhibited and therefore desire the present embodiment to be considered as illustrative and not restrictive, referring to the appended claims rather than to the foregoing description to indicate the scope of the invention.

Having described my invention, what I

claim as new and desire to secure by Letters Patent is:

1. A built-up sole for a "turn" type of shoe, consisting in a middle sole member, an outer sole member secured thereto by peripheral stitching, and a welt secured to said middle sole member by stitching extending only through said middle sole member and said welt, the inner edge of said welt being formed and adapted to receive a stitching line for securing it to an upper while in reversed position on a last, according to the turn method.

2. A built-up sole for a "turn" type of shoe, consisting in a welt, a sole member secured to the outer portion of said welt by means extending through said sole member and said welt only, the inner edge portion of said welt being adapted to receive a line of stitching securing it to an upper while in reversed position on a last, and an outer sole member secured peripherally to both said welt and said first named sole member.

3. A built-up sole for a "turn" type of shoe, consisting in an outer sole member, a middle sole member, a heel piece interposed between said members, means for uniting said members adjacent their peripheral edge, and a welt secured to said middle sole member by a line of stitching extending only through it and said middle sole member, the inner edge of said welt being adapted to receive a line of stitching for securing it to an upper while in reversed position on a last.

4. The herein described method which consists in securing a welt member to a middle sole member by stitching extending through said members only, then securing an outer sole to said members, and then securing an upper to the inner edge of said welt by stitching through said welt while the sole and the upper are in reversed position on a last.

In testimony whereof, I have signed my name to this specification.

JOHN E. SCOTT.
